UNITED STATES PATENT OFFICE

156,915

DENTAL LATHE

Erle J. Pow, Woodstock, Ontario, Canada

Application November 26, 1947, Serial No. 142,823

Term of patent 3½ years

(Cl. D54—6)

To all whom it may concern:

Be it known that I, Erle J. Pow, a citizen of the Dominion of Canada, residing in the city of Woodstock, in the county of Oxford, in the Province of Ontario, Canada, have invented a new, original, and ornamental Design for a Dental Lathe, of which the following is a specification, reference being had to the accompanying drawing, forming a part thereof.

In the drawing:

Figure 1 is a front perspective view of a dental lathe showing my new design,

Figure 2 is a side perspective view of Figure 1,

Figure 3 is a rear perspective view of Figure 1, and

Figure 4 is a side perspective view of the opposite side of the dental lathe, to that shown in Figure 2.

I claim:

The ornamental design for a dental lathe, substantially as shown.

ERLE J. POW.
